US00D740804S

(12) **United States Design Patent**
Hovdal

(10) **Patent No.:** **US D740,804 S**
(45) **Date of Patent:** **** Oct. 13, 2015**

(54) **CONTROL PAD DEVICE**

(71) Applicant: **Cisco Technology, Inc.**, San Jose, CA
(US)

(72) Inventor: **Gaute Hovdal**, Jar (NO)

(73) Assignee: **Cisco Technology, Inc.**, San Jose, CA
(US)

(**) Term: **14 Years**

(21) Appl. No.: **29/473,111**

(22) Filed: **Nov. 19, 2013**

(51) LOC (10) Cl. **14-02**

(52) U.S. Cl.

(57) **CLAIM**

The ornamental design for a control pad device, as shown and described.

DESCRIPTION

FIG. 1 is a front perspective view of the control pad device; FIG. 2 is a rear perspective view of the control pad device; FIG. 3 is a front elevation view of the control pad device; FIG. 4 is a rear elevation view of the control pad device; FIG. 5 is a top plan view of the control pad device; FIG. 6 is a bottom plan view of the control pad device; FIG. 7 is a side elevation view of the control pad device; and, FIG. 8 is a side elevation view of the control pad device. The broken lines shown in the drawings illustrate portions of the control pad device that form no part of the claimed design.

1 Claim, 6 Drawing Sheets
